(Cl. D30—1)

To all whom it may concern:

Be it known that we, George Frederick French, Roger French, and Samuel Warburton, subjects of the King of Great Britain and residing at Manchester, England, have invented a new, original, and ornamental Design for a Cartridge Belt Link, of which the following is a specification, reference being had to the accompanying drawing, forming part thereof.

Fig. 1 is a perspective view of a cartridge belt link, showing our new design;

Fig. 2 is a top plan view; and
Fig. 3 is an end view.

We claim:

The ornamental design for a cartridge belt link, as shown.

GEORGE FREDERICK FRENCH.

ROGER FRENCH.

SAMUEL WARBURTON.
